PLATE OR SIMILAR ARTICLE

Seiichi Makita, Nagoya, Japan, assignor to Noritake Co., Limited (Nippon Toki Kabushiki Kaisha), Shin-machi, Nishi-ku, Nagoya, Japan

Filed Apr. 25, 1975, Ser. No. 571,662

Claims priority, application Japan Nov. 6, 1974

Term of patent 7 years

Int. Cl. D7—01

U.S. Cl. D7—23

FIG. 1 is a plan view of a plate or similar article embodying my new design; and

FIG. 2 is a side elevational view thereof partly in section.

The surface decoration has been omitted from the interior of the plate in FIG. 2 for convenience of illustration.

I claim:

The ornamental design for a plate or similar article, as shown and described.
